CATHODE STRUCTURES

James E. Beggs, Schenectady, N. Y., assignor to General Electric Company, a corporation of New York

Application October 22, 1954, Serial No. 464,078

8 Claims. (Cl. 313—340)

This invention relates to cathode structures and methods of forming the same. While the cathode structures of this invention are subject to many variations and modifications they are ideally suited for utilization in miniature electric discharge devices and will be particularly described in this connection.

It is generally desirable that the electron emitting surface of an electric discharge device be brought up to operating temperature at a rapid rate and remain substantially stationary throughout the entire range of operating temperatures. Conductors having a relatively large surface per unit volume can be rapidly heated and will transfer a large portion of this heat at a rapid rate to another member in contact therewith. However, thin conductive members, such as foil, are unduly flexible and tend to change their shape and position upon heating. It is therefore an important aspect of this invention to provide a fast heating foil structure which is relatively rigid while still maintaining a relatively high rate of heat transfer to an electron emitting surface.

It is also desirable that the current supplied to the heating element be supplied in a symmetrical path so that the inherent inductance of the current flowing through the heater leads is effectively cancelled and further so that all areas of the heated element are uniformly and rapidly heated. In addition, the cathode structure should have a low inductance, particularly to radio frequency currents.

It is therefore an important object of this invention to provide an improved cathode structure and method of forming cathode structures.

It is also an object of this invention to provide improved cathode structures having inherently low inductance and which can be rapidly and uniformly heated.

A further object of this invention is to provide efficiently and rapidly heated cathode structures having symmetrical heater circuits and methods of forming these structures.

Another object of this invention is to provide an improved rigid cathode structure capable of sustained high temperature operation.

According to an important aspect of this invention, there is provided a cathode structure and method of forming a cathode structure which includes a foil member and an electron emitting surface oriented in heat conducting relationship to said foil member to provide a low inductance uniformly and quickly heated cathode structure.

Other important aspects and objects of this invention will become more apparent when the following specification and claims are considered in connection with the figures of the drawing in which Figure 1 illustrates a U or channel-shaped cathode formed in accordance with this invention; Figures 2 and 3 illustrate a modification of the cathode illustrated in Figure 1; Figure 4 illustrates a cathode with a foil heater element; Figures 5a and 5b illustrate a foil heater and the adaptation of this foil heater to directly heat a cup-shaped cathode; Figure 6 il-

lustrates a cathode and heater structure and Figures 7 to 13, inclusive, illustrate modified cathode structures wherein a conductive film is formed on an insulating member to provide a heater.

Figure 1 illustrates a directly heated cathode assembly of the filamentary type which is formed of a foil clad member consisting of backing 10 with foil covering 11. The cathode is formed, for example, by stamping the backed foil into the desired channel or U-shape and then removing backing metal 10, for example, by applying an acid bath which dissolves the backing metal. A portion of the backing metal 10 is left at the ends of the cathode structure to assist in attaching heater leads and in mounting the cathode structure. An appropriate emissive coating, such as the conventional triple carbonate coating, is then applied to the top surface 12 after which the cathode assembly is mounted in an electric discharge device and activated.

For example, where it is desired to form a cathode which is capable of operating at sustained high temperatures, the cathode structure is formed from a sheet of steel approximately 10 mils thick having a molybdenum foil coating approximately .25 mil thick. The cathode is formed and then the steel is dissolved from the molybdenum by applying a hydrochloric acid solution.

In this manner, an extremely strong and rigid foil cathode structure is formed without the attendant hazard of cracking or breaking the foil which is present when a cathode is formed from unbacked foil. A cathode of this type is particularly suited for utilization as a direct heating cathode and can be brought up to operating temperature in a very short period of time, i. e., in the order of one quarter of a second.

It is readily apparent that this process and the form of cathode herein illustrated, by way of example, is subject to a number of variations in shape and form and may be constructed of any foil material which forms a satisfactory cathode base and may, for example, consist of such materials as iron, molybdenum, nickel, tungsten, titanium, zirconium or tantalum.

For example, an active barium oxide electron emitting surface can be fabricated on a titanium base without the formation of an interface, and which is capable of high level stable emission at relatively low cathode temperatures. The oxide coating is readily reduced by the titanium, at a rate depending upon the cathode temperature, so that barium is formed and oxygen is absorbed by the titanium without the formation of a film or interface on the surface of the titanium base and thereby results in cathode emission which is stable at high current densities even when operated in the emission limited region. The emission life of a titanium cathode can be increased by utilizing one or more of the oxides of strontium or calcium or combinations thereof with barium oxide, since strontium and calcium oxides are reduced by titanium more slowly than is barium oxide.

Figures 2 and 3 illustrate a manner in which a cup-shaped cathode structure can be formed from a strip or ribbon of foil 13 so as to provide a cathode structure consisting of a substantially flat top surface 14 having cylindrical skirt members 15 and 16. This cathode, for example, is formed with a punch press or may be formed by spinning a strip or ribbon of foil on a lathe. It is apparent that this structure can be formed from backed foil material from which the backing metal is removed after forming.

The structure illustrated in Figure 3 has the additional feature of having a substantially circular top surface and substantially cylindrical sides which lend an additional degree of rigidity to the final structure. The top surface 14 is coated with an emissive coating and the slot 17, which is present when a thin strip or ribbon is

so formed, or can be cut into a cup which is punched out of a flat disk or slug of metal, provides the two heater leads and results in an inherently non-inductive cathode structure.

This structure can be adapted for utilization as an indirect heater for a cathode structure such as that illustrated in Figure 4 wherein a cathode structure 18 similar to that illustrated in Figure 3 is supported in heat conducting relationship with, but out of direct contact with inverted cup 19, on the top surface 20 of which 10 is placed a suitable emissive coating. Cup 19 is supported, for example, in ceramic insulator 21 which is provided with a plurality of projections 22 which make contact with and are bonded to the cathode. The projections limit the heat transfer to the insulator and increase the efficiency of the cathode. The cathode connection is made by applying a conducting film to the lower surface of insulator 22 so that radio frequency currents flow over the entire surface of cup 19 and result in a low inductance cathode connection.

Cathodes of the form illustrated in Figures 3 and 4 have inherently low inductance so that they are ideally suited for utilization in miniature electric discharge devices operated at high frequencies. Since the electrically heated cathode structure is formed of extremely thin foil material, it can be very rapidly heated and in view of the inherent rigidity of the shape into which it is formed, a cathode structure utilizing a heater element of this type is less subject to microphonics than are other forms of heaters.

Figures 5 and 6 illustrate modified versions of directly heated cathode structures utilizing at least one conductive foil member having an electron emitting surface oriented in intimate heat conducting relationship to the foil member. Figure 5a illustrates two substantially L-shaped foil strips or ribbons 23 and 24 having angularly oriented top portions 23' and 24' which are rounded so as to fit into and be bonded to the inner surface of inverted foil cup 25. The cup has a substantially flat surface 26 on which an emissive coating is formed and the entire cathode structure is, for example, retained in metal disk 27 which provides an inherently low inductance conducting path to surface 26.

The cathode structure is formed by suitably bonding ribbons 23 and 24 together along the length thereof and then bonding the heater to the inner surface of the cup 25. The bonding may be effected by spot-welding, brazing or other suitable metal-to-metal bonding such as is disclosed in my copending application Serial No. 409,159 filed February 9, 1954 and assigned to the same assignee as this invention.

The cup consists of metal, such as titanium, zirconium, iron-nickel alloy, tantalum or other metal, which forms a satisfactory cathode base and, for example, is formed from foil or from backed foil. For example, the cup can be formed from titanium foil clad steel wherein the steel is dissolved in hydrochloric acid after the cup is formed or, alternatively, it may be fabricated by joining a shallow foil cup or disk and a thin foil cylinder.

The ribbon heater is formed, for example, of a ribbon of titanium, zirconium, iron-nickel alloy, tantalum or other metal which can be satisfactorily bonded to an inner surface of the cup 25. The cross section of the ribbon heater is such that it heats with approximately the same current as will heat the cup to which it is attached so that the entire structure is uniformly and rapidly heated, i. e., the foil and the cup form the heating element. Since the cup has relatively low heat conductivity, as a result of the choice of material and its relative thinness, the heat loss from the sides of the cup is relatively small and the efficiency of the resulting cathode structure is high.

An alternative form of a directly heated foil cathode is illustrated in Figure 6 wherein foil cathode cup 28 is provided with a centrally oriented heater lead 29 ter-

minating in a tapered end portion 30 which extends out to contact an area within cup 28 substantially the same as and contiguous with the emitting surface 31. The heater lead 29 and tapered end portion 30 have such dimensions that approximately the same current heats the lead as will heat the cup 28 and so that the entire structure is uniformly and rapidly heated.

It will be readily apparent that the cathode structures herein described can be modified, for example, by forming a convex or concave emitting surface and, for example, by utilizing an electron emitter other than the aforementioned triple carbonate coating.

It is further noted that where a higher resistance heater is desired, a ceramic button or refractory coating can be formed on the inner end surface of cup 25. A conducting film can then be formed by applying a coating of carbon containing compound, such as a nitrocellulose binder, to the ceramic button and then applying at least one metal from the group consisting of titanium, zirconium, hafnium, and thorium and at least one metal from the group consisting of, but not limited to, iron, nickel, cobalt, copper, chromium, platinum and molybdenum so that when heated a conducting film, including at least one metal from these groups, is formed. Conducting films of this type are more completely described in my copending application Serial No. 464,080 filed herewith and assigned to the same assignee as this application.

Figure 7 illustrates a form of resistance heater utilizing the method disclosed and claimed in the above-identified patent application wherein there is shown foil cup 32 having a top surface 33 on which emissive coating 34 is applied. Within the cup a thin disk or wafer 35 of insulating material, such as a ceramic of the type commonly referred to as alumina, is suitably bonded to the top surface of the cup. A conducting heater film 36 is formed over a portion of or all of the lower surface of ceramic disk 35 and heater lead 37 connects to a central portion of the conducting film 36. Heating is effected by current flow through heater lead 37 to film 36 and down through the cup-shaped foil member 32.

It is noted that the foil cup can be punched or otherwise formed in accordance with the previously described process or the cup can be formed by suitably bonding or brazing top member 33 to a cylinder of foil 32 at the same time the ceramic disk or wafer is bonded to the top member. A method of effecting such a bond between ceramic and metal members is described in my aforementioned copending application, Serial No. 409,159.

Alternatively, a coating of high temperature clay or other refractory material can be substituted for the thin ceramic wafer. The surface is coated with a conducting film to which is brazed the center connecting heater lead 37. When voltage is applied, the conductive film becomes hot, thereby heating the electron emitting surface to which it is attached. The conductive film can be made to operate at voltages in the order of 90 volts, in which case it can be operated from a plate battery supply, and thereby eliminate the need for a separate heater supply.

The rigidity of the insulating film or ceramic wafer serves to keep the foil surface from warping or buckling. Since heat is applied almost directly in contact with the emitting surface, and the heater temperature for all practical purposes is the same as the cathode temperature, the heating efficiency is high and the heat radiated to the foil cylinder is relatively low. These features along with the low mass of the assembly combine to produce a thermally and mechanically stable cathode.

Figure 8 illustrates a cathode shell 39 having a resistance heater 40 formed on ceramic disk or wafer 41 and connected by heater leads 42 and 43. Figures 9 through 13, inclusive, illustrate modifications of the heater pattern illustrated in Figure 8. For example, heaters illustrated in Figures 9 through 11, inclusive, are particularly suited

for utilization in separately heated cathode constructions and those illustrated in Figures 12 and 13 are particularly suited for heaters wherein the cathode cup or emitting surface forms a part of the heater circuit. Each of these heater patterns is formed on a ceramic button or disk of material such as, for example, those ceramics generally classified as steatites, forsterites and aluminas.

It is noted that the ceramic button or disk 41 can be covered with a nitrocellulose coating over the entire area or in the form of the pattern illustrated in Figures 9 through 13, inclusive. When a high heater voltage is required, these films are usually of a type consisting essentially of carbon while, when low heater voltages are desired, the coating includes metal additives so as to result in a conducting film having a positive, zero, or negative thermal coefficient of resistance. Examples of such films and methods of forming the same are described in greater detail in my aforesaid copending application Serial No. 464,080.

Cathodes of the type herein disclosed are ideally suited for utilization in electric discharge devices such as those described in my Patent No. 2,680,824 and my copending application Serial No. 464,079 filed herewith, both of which are assigned to the same assignee as this invention.

It is readily apparent that the cathode structures of this invention have inherently low inductances and in particular those illustrated in Figures 5 through 8 provide a substantially symmetrical heater current path which has inherently low inductance. The metal ring, or the ceramic ring with a conducting coating thereon, which retains the cathode provides an inherently low inductance conducting path to the emissive surface which extends over the sides of the cathode. The intimate heat conducting contact between the heater and the emitting surface provides a structure which is rapidly heated to operating temperature, i. e., in the order of one quarter to three quarters of a second, and which structure is relatively rigid because of the shape thereof so that the tendency toward microphonics is minimized.

This invention has been described in connection with a limited number of specific examples so that a complete understanding thereof may be had; however, it will be readily apparent that this invention is subject to many modifications and it is intended in the appended claims to cover all modifications coming within the true spirit and scope of this invention.

What I claim as new and desire to secure by Letters Patent of the United States is:

1. A cathode structure for an electric discharge device comprising a cup-shaped member including side wall and an end wall having an electron emissive coating on an exterior surface thereof, a thin insulating disk in contact with the interior of said end wall and a thin film on the exposed surface of said disk and having a much greater resistance than said cup-shaped member, said film extending to said side walls for providing a heater element in closely coupled thermal relation with substantially all of said end wall and an electrical connection with said film heater at a point remote from the side walls of said cup-shaped member.

2. A cathode structure for an electric discharge device comprising a cup-shaped member including an end wall having an electron emissive coating on an exterior surface thereof, a thin insulating disk in contact with the interior of said end wall, a resistance heater element bonded to the exposed surface of said insulating disk closely coupled thermal relation with substantially all of said end wall, said resistance element having a much greater resistance than the resistance of said cup-shaped member, and leads for connecting an energizing circuit to said resistance element.

3. A cathode for an electric discharge device comprising a thin metallic support, an electron emissive coating on said support on one side thereof, a thin insulat-

ing wafer in contact with the opposite side of said support and substantially coextensive in area with said coating, a thin conductive film formed on the opposite side of said wafer to provide a heater in closely coupled thermal relation with substantially all of the coated area of said support, said film having a much greater resistance than the resistance of said support, an electrical connector connected with said conductive film at a central point thereof, and another electrical connector connected to said conductive film at, at least, one point on the periphery thereof.

4. A cathode for an electric discharge device comprising a thin metallic support, an electron emissive coating on said support on one side thereof, a ceramic wafer in contact with the opposite side of said support and substantially coextensive in area with said coating and a thin metallized film formed on the opposite side of said ceramic wafer in electrical contact with the periphery of said thin metallic support around the coated area to provide a heater in closely coupled thermal relation with substantially all of the coated area of said support, said film having a much greater resistance than the resistance of said support.

5. A cathode for an electric discharge device comprising a thin metallic support, an electron emissive coating on said support on one side thereof, a thin ceramic wafer in contact with the opposite side of said support and substantially coextensive in area with said coating, and a thin metallized film formed on the opposite side of said ceramic wafer and in electrical contact with said thin metallic support at the periphery of the coated area to provide a heater in closely coupled thermal relation with substantially all of the coated area of said support, said film including a metal selected from the group consisting of titanium, zirconium, hafnium and thorium, said film having a much greater resistance than the resistance of said support.

6. A cathode for an electric discharge device comprising a thin metallic support, an electron emissive coating on said support on one side thereof, a thin ceramic wafer in contact with the opposite side of said support and substantially coextensive in area with said coating, and a thin metallized film formed on the opposite side of said ceramic wafer and in electrical contact with said metallic support at the periphery of the coated area to provide a heater in closely coupled thermal relation with substantially all of the coated area of said support, said film including a first metal selected from the group consisting of titanium, zirconium, hafnium and thorium, and a second metal selected from the group consisting of iron, nickel, platinum, chromium, copper, cobalt and molybdenum, said film having a much greater resistance than the resistance of said support.

7. A cathode structure for an electric discharge device comprising a cup-shaped member having an end wall, one side of said end wall providing an electron emissive coating, a pair of L-shaped conducting ribbons each having one leg in contact with the end wall of said member, and the other legs thereof positioned in back-to-back relation and extending substantially perpendicular to said end wall, said L-shaped conducting ribbons having a combined resistance approximately equal to the resistance of said cup-shaped member so that when a heating current is conducted through said ribbons and said cup-shaped member said ribbons and said cup-shaped member are rapidly and substantially uniformly heated.

8. A cathode structure for an electric discharge device comprising a thin conducting cup-shaped member including an end wall having an electron emissive coating on an exterior surface thereof, a conductor approximately centrally oriented within said cup-shaped member, said conductor having a tapered end portion extending out to contact substantially all of said end wall, the resistivity of said conductor being of the order of the resistivity of said cup-shaped member and the cross-sectional area

of said conductor and said cup-shaped member being such that upon passage of a heater current therethrough, said conductor and said cup-shaped member are rapidly and substantially uniformly heated.
